UNITED STATES PATENT OFFICE.

HAROLD F. ELLIOTT, OF PALO ALTO, CALIFORNIA, ASSIGNOR TO AUGUSTUS TAYLOR,
OF SAN FRANCISCO, CALIFORNIA.

ARC-RADIO-OSCILLATION GENERATOR.

1,385,121.

Specification of Letters Patent. Patented July 19, 1921.

Application filed March 23, 1920. Serial No. 368,194.

To all whom it may concern:

Be it known that I, HAROLD F. ELLIOTT, a citizen of the United States, and a resident of Palo Alto, county of Santa Clara, and State of California, have invented certain new and useful Improvements in Arc-Radio-Oscillation Generators, of which the following is a specification.

The invention relates to arc radio oscillation generators and particularly to the construction and arrangement of the electrodes between which the arc is formed.

An object of the invention is to provide means for restricting the arc to a narrow sheet of flame.

Another object of the invention is to provide means for holding the arc steady and prevent it from wobbling and wandering around on the anode.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one embodiment of my invention, but it is to be understood that the invention is not limited to such form, since the invention, as set forth in the claims, may be embodied in a plurality of forms.

Referring to said drawings:

Figure 1 is a side view of the anode showing the relation thereto of the magnetic field poles.

Fig. 2 is a plan view showing the electrodes over a field pole.

Fig. 3 is a horizontal section of the anode in its environment with respect to the cathode.

I have found that there is considerable tendency for the arc to wobble and wander around on the anode with occasional jumping to the magnetic field pole tips. This tendency of the arc to jump to the pole tips has been overcome by reducing the voltage across the arc which consequently reduced the power output of the generator. In accordance with my invention, the arc flame is guided, which produces steadier operation of the generator and the arc does not wobble

or jump to the magnet poles, so that a higher voltage may be impressed on the arc, or for a given voltage the magnet pole tips may be placed closer together, reducing the magnetic air gap and permitting the use of smaller magnet coils.

The arc is formed between the anode 2 and cathode 3, which are disposed between the magnet pole tips 4. By making the tip 5 of the anode cylindroconoidal in form or in other words, in the shape of the nose of a bullet or projectile, the arc is restricted to a narrow sheet of flame and does not wander over the surface of the anode. The tip 5 is preferably formed of copper and may be brazed to or formed integral with the hollow anode 2, which is also preferably formed of copper. The anode is cooled by a jet of cooling liquid discharging from the tube 6 arranged within the anode.

The cathode 3, which is usually formed of carbon, is preferably arranged at a right angle to the anode, with the tip of the cathode spaced back slightly from the end of the anode tip so that the arc is formed substantially as shown in Fig. 3. The arc thus formed remains steady and results in a more uniform output of the generator.

I claim:

1. In an arc radio generator, a metallic anode having a cylindroconoidal tip and a carbon cathode arranged at an angle to said anode and adjacent said tip.

2. In an arc radio generator, a hollow metallic anode, a cylindroconoidal tip on said anode and a cathode disposed at a right angle to the anode with the cathode tip spaced backward from the end of the anode tip.

3. In an arc radio generator, a metallic anode having a cylindroconoidal tip and a cathode arranged at right angles to the anode, with the end of the cathode adjacent the tip.

In testimony whereof, I have hereunto set my hand at Palo Alto, California, this 12th day of March, 1920.

HAROLD F. ELLIOTT.

In presence of—

CARL E. SCHOLZ,
RUBY SHEPARD.
